UNITED STATES PATENT OFFICE.

JOHN FRED LOBER, OF PITTSBURG, PENNSYLVANIA.

MACHINE FOR MAKING COUPLING-PINS, &c.

SPECIFICATION forming part of Letters Patent No. 760,883, dated May 24, 1904.

Application filed June 18, 1903. Serial No. 162,117. (No model.)

To all whom it may concern:

Be it known that I, JOHN FRED LOBER, a citizen of the United States, and a resident of Pittsburg, in the county of Allegheny and State of Pennsylvania, have invented certain new and useful Improvements in Machines for Making Coupling-Pins, &c., of which the following is a specification.

The primary object of the invention is to provide a machine for making coupling-pins and similar articles in which the article is formed at a single operation by forging or compressing the stock in opposing dies, one of which latter is longitudinally movable and separable, so as to release the completed article and permit of its being ejected from the machine, the parts of the said separable die closing at the proper time to receive the stock and present practically a solid die in forming the coupling-pin.

The invention consists in the particular construction and combination of parts embodying the invention, all as hereinafter described and specifically claimed.

In the accompanying drawings, forming a part of this specification, Figure 1 is a side elevation of a machine constructed in accordance with my invention. Fig. 2 is a plan view of the machine, the full lines showing the movable die separated and the dotted lines the position the same assumes in forging the coupling-pin. Fig. 3 is a sectional view on the line 3 3 of Fig. 2, the longitudinally-movable and separable die being shown in its forward or closed position. Fig. 4 is a similar view looking in the opposite direction or toward the stationary die. Fig. 5 is a detail view of the die carried by the longitudinally-movable and separable die-holders. Fig. 6 is a similar view of the stationary die. Fig. 7 is a detail side elevation of the longitudinally-movable part of the movable die-holder. Fig. 8 is a similar view of the other part of said movable die-holder. Fig. 9 is a view of the completed coupling-pin.

Referring to said drawings, A designates the bed of the machine, which is supported at a suitable height by means of the legs a and is composed of the side pieces A' and A², connected at their forward ends by a cross-piece

A³, having a head A⁴ formed therewith, the latter supporting the stationary die herein-after described. The rear end of the bed of the machine is contracted in width, and upon the side pieces thereof are mounted boxes b b, 55 in which is journaled the main shaft B, carrying the fly-wheels B' B' and a belt-pulley b'. Between the side pieces said shaft is provided with a crank b², to which is connected a rod b³, attached to the movable die C for reciprocating the same.

The side piece A' of the bed-frame of the machine is formed at its lower end with an inwardly-projecting horizontal flange a', forming a track upon which slides the part 65 C' of the movable die-holder, and let into the upper surface of said side piece is a guide-plate D, between which latter and the aforesaid flange or track the said part C' slides. The side piece A² of the bed-frame is also 70 formed at its lower end with an inwardly-projecting flange a², wider than the aforesaid flange a' and stepped, as shown. Upon the lower step or offset, at the inner end thereof, is secured a plate e, the upper surface of 75 which is flush with the step above and its outer edge beveled to engage a corresponding bevel of the laterally-projecting portion e' of the part C', before mentioned. In this manner the said part C' is permitted to have a 80 direct longitudinal movement only, the said movement being imparted by the connecting-rod b³ from the main shaft.

C² designates the other part of the movable die-holder, the same being adapted to have 85 both a longitudinal movement with the part C' and a lateral movement independent thereof. To this end the part C² is mounted within the part C' and upon the plate or slide e and is guided in its longitudinal and lateral movements by means of a cam-plate F, the latter having a flange which engages a groove in the outer side of said part C². The parts C' and C² are connected by a pin g, which is fast to and extends from a boss e' on the part 90 C² through a corresponding boss e' on the part C' and projects beyond the latter to engage a cam-plate h, bolted on the bed-plate of the machine. This cam-plate h, in connection with the pin g, serves to impart a lateral 95 movement to the part C². The part C² is 100

2 motion to the part C² as the die-holder is reciprocated.

Each part C' and C² of the movable die-holder is provided at its inner side with a recess in which is held the sectional die I, consisting of two sections held in the aforesaid die-holder parts, respectively, by means of set-screws i. This die is adapted to form the head of the coupling-pin, and the cavity 10 therein is therefore shaped as shown in Fig. 5.

The stationary die (designated by the letter J) is made up preferably of two parts, which are inserted in the head A⁴ and held therein by the top plate a⁵. The stationary die bears 15 at its rear end against a breastplate L, having an integral shank which passes through the head and is threaded at its outer end to receive a nut l, by which the said breastplate is held rigidly in place. The stationary die 20 forms the point of the pin, and the cavity is therefore shaped as shown in Fig. 6.

For the purpose of adjusting the cam-plate F and plate e laterally adjusting-screws f' and e' are provided, being threaded in the side 25 piece A², similar set-screws, as d, being threaded in the side piece A' for adjusting the guide-plate D, these adjustments taking up any wear. Provision is also made for longitudinally adjusting the cam-plate F by means of a set-screw f, threaded in a boss a⁶ at the forward 30 end of the bed-plate.

N designates a transverse shaft which is located above the bed-frame of the machine and supported in boxes n, secured to upper ends 35 of standards m, which latter are formed integrally with the side pieces of the bed-frame. The boxes are formed with depending pins o, by which they are secured to the standards, said pins being engaged by transverse pins o' 40 and a set-screw o². To the shaft N is secured a forwardly-projecting arm P, having at its forward end a depending finger p, which latter serves to eject the completed coupling-pin, and to insure its proper engagement there- 45 with said pin is bifurcated at its lower end. This ejector is operated from the main shaft by a rearwardly-projecting arm R, which latter is raised and lowered by a cam-lever S, mounted on the main shaft B.

50 In the operation of the machine a bar of metal, as x, Fig. 2, is placed in the stationary die while the movable die is in its rearward position, and as said movable die approaches the stationary die the laterally-movable part C² of the former first closes against the part C' and upon the outer end of the bar of metal or stock, and a further forward movement presses the stock into the die I, which latter thereby forms the head of the coupling-pin simultaneously with the forming of the point in the stationary die. After the coupling-pin is formed the movable die moves rearward, and the pin g, riding upon the cam-plate h, slides the part C² of the separable die-holder laterally or away from the part C', releasing the

coupling-pin, which is then ejected from the die by means of the ejector P, which latter is operated at the proper time by the cam-lever S. Another bar is inserted in the stationary die and the operation repeated, and so on. It 70 will be understood that the sections of the longitudinally-movable die close on the bar or stock x just prior to the limit of its forward movement, so that a comparatively solid die will be presented in which to press or forge 75 the pin.

The machine is automatic in its operation except in so far as to require an attendant to feed the bars of metal into the stationary die, and as said bars are at red heat they are of 80 course handled by tongs.

Though I have shown the machine provided with dies for making coupling-pins with heads and shoulders, it will be understood that other styles of coupling-pins may be forged in the 85 machine and that other articles may be made thereby.

Having thus described my invention, what I claim as new, and desire to secure by Letters Patent, is—

90 1. In a machine for making coupling-pins, &c., the combination with the stationary die, of a movable die composed of two parts one of which has a direct longitudinal movement in guides and the other a longitudinal movement therewith and lateral movement therein, means for imparting said longitudinal movement, and means for imparting said lateral movement.

95 2. In a machine for making coupling-pins, &c., the combination with the stationary die, 100 of a movable die composed of two parts one of which has a direct longitudinal movement in guides to and from the stationary die and the other a longitudinal movement therewith and lateral movement therein; a reciprocating rod 105 attached to the first-mentioned part, and cams for imparting the lateral movement to the last-mentioned part of the die, substantially as shown and described.

110 3. In a machine for making coupling-pins, &c., the combination with the stationary die, of a die composed of two parts one of which is extended laterally to form guides in which the other is slidable laterally, means for longitudinally reciprocating the first-mentioned 115 part of the die, and means for laterally moving the other part of said die, substantially as shown and described.

120 4. In a machine for making coupling-pins, &c., the combination with the stationary die, 125 of a die comprising two parts longitudinally movable to and from the stationary die and slidable laterally one within the other, means for imparting such longitudinal movement, a pin fixed to one of the parts and slidable in the other, and a cam-plate upon which the outer end of the pin travels, whereby one of the parts of the movable die is moved to and from the other as said die is reciprocated.

130 5. In a machine for making coupling-pins,

&c., the combination with the stationary die, of a die comprising two parts slideable longitudinally in guide-plates, means for imparting such longitudinal movement, a pin fixed to one 5 of the parts and slideable in the other projecting beyond the latter, a cam-plate upon which the outer end of the pin is adapted to travel, and an opposite cam-plate adapted to guide the laterally-movable part of the die, substantially as shown and described.

6. In a machine for making coupling-pins, &c., the combination with the stationary die, of a die comprising two parts longitudinally movable in the machine to and from the stationary die and slideable laterally one within the other, means connected to one of the parts for imparting a longitudinal movement thereto, a pin slideably connecting the parts, and opposite cam-plates for operating the laterally-movable part of the die, together with an ejector operated by a cam-lever on the main shaft and adapted to eject the finished pin when the parts of the separable die are open.

7. In a machine for making coupling-pins, &c., the combination with the bed-frame, of a stationary die at one end thereof, longitudi-

nal guide-plates at opposite sides of the frame, a die comprising two parts one having a direct longitudinal movement between said guide-plates to and from the stationary die and the other longitudinal and lateral movements, means connected to the longitudinally-movable part of the die for imparting such movement thereto, a cam-plate F, serving as a guide for the laterally-movable part, a pin fixed to 35 said laterally-movable part and projecting through a boss on the other part, and a cam-plate h, upon which the end of the pin is adapted to ride, the cam-plates being so disposed that the parts of the movable and separable 40 die will close a short distance from the stationary die; together with means for ejecting the finished coupling-pin when the parts of the movable die are open.

In testimony whereof I have signed my 45 name to this specification in the presence of two subscribing witnesses.

JNO. FRED LOBER.
